UNITED STATES PATENT OFFICE

160,163

NARROW LACE OR THE LIKE

Abraham Gottlieb, New York, N. Y.

Application December 28, 1948, Serial No. 150,412

Term of patent 3½ years

(Cl. D47—6)

To all whom it may concern:

Be it known that I, Abraham Gottlieb, a citizen of the United States, residing in the Borough of Manhattan, city, county, and State of New York, have invented a new, original, and ornamental Design for Narrow Lace or the like, of which the following is a specification, reference being had to the accompanying drawing, forming part thereof.

On the drawing, the figure is a plan view of a narrow lace, or the like, showing my new design.

The narrow lace is shown against a dark background, to bring out the details of the design.

The unit repeats beyond the dot-and-dash lines in regular succession.

I claim:

The ornamental design for a narrow lace or the like, substantially as shown and described.

ABRAHAM GOTTLIEB.
